UNITED STATES PATENT OFFICE

1,927,876

AMUSEMENT MACHINE

John F. Meyer, Chicago, Ill.

Application August 8, 1929. Serial No. 384,272

6 Claims. (Cl. 273—101)

This invention relates to amusement machines and it has for its primary object to provide a novel machine of the shooting gallery type provided with movable and stationary targets and 5 or more coin operated pistols combined and arranged in a portable machine adapted to be displayed in public and other places and to furnish entertainment and amusement to the general public.

10 Another object of the invention is to provide two or more oppositely movable carriers traveling at different speeds and having targets mounted thereon.

Another object of the invention is to provide a 15 plurality of movable targets pivotally mounted to fall over when struck and means for automatically restoring the down targets to upright position.

A further object of the invention is to provide 20 means of simple construction for operating the movable targets in a regular and orderly manner whether or not any of the targets are struck by balls.

And a further object of the invention is to 25 construct and arrange the movable and other parts and mechanisms of the machine so that the balls will not be obstructed thereby and will not interfere with the operation thereof and also to provide means for quickly returning the balls 30 to the pistols and without interfering with the operation thereof.

A further object is to arrange the pistols and associated parts as detachable units which can be packed within the cabinet for shipping purposes.

A further object is to provide an improved 35 coin receiver which will be inexpensive to manufacture and which will be very difficult of access by unauthorized persons.

40 A further object is to improve the construction, arrangement and operation of the machine shown and described in my copending application Serial No. 349,355, filed March 23, 1929.

45 Other objects will appear hereinafter.

Fig. 1 is a front elevation of an amusement machine embodying my invention;

Fig. 2 is a plan section on the line 2—2 of Fig. 6;

50 Fig. 3 is a vertical section on the line 3—3 of Fig. 6;

Fig. 4 is a vertical detail section on the line 4—4 of Fig. 6;

55 Fig. 5 is a detail section of one of the target uprighting devices;

Fig. 6 is a vertical section on the line 6—6 of Fig. 1;

Fig. 7 is a detail of the means for maintaining the target in upright position after they leave the range;

Fig. 8 is an enlarged detail elevation of the ball receiving tray and the counter actuating device;

Fig. 9 is a detail plan of the ball receiving tray and the parts related thereto;

Fig. 10 is an interior end view of the cabinet 65 with the door open to show the manner in which the pistol unit is mounted for shipment;

Fig. 11 is a detail section showing the manner of holding the pistol in operating position in front of the cabinet;

Fig. 12 is a detail section of the track, target and traveling belt on the line 12—12 of Fig. 3;

Fig. 13 is an enlarged detail section on the line 13—13 of Fig. 4;

Fig. 14 is a detail section of a stationary target; 75 and

Fig. 15 is a detail plan of the target uprighting device on the line 15—15 of Fig. 5.

Referring to the drawings the invention comprises a cabinet 1 having in the upper part there-

80 of a glass front 2 for one or more ranges, two being shown in the drawings separated by a glass partition 3. There is a door 4 at the back of the cabinet to permit access to the interior thereof, and one or more lights 5 at the top of the cabi-

85 net, and at the rear thereof, with a barrier 6 de-pending from the top of the cabinet in front of the lights to hide the lights from the spectators. This arrangement of the lights and the barrier gives the effect of indirect lighting upon the tar-

90 gets beneath the lights. The bottom of the ranges is formed by an inclined plate 7 which is suitably supported in the cabinet above the operating mechanism and adjoins at the rear a

95 more sharply inclined support 8 which extends transversely of the cabinet and is provided with track grooves 9, 10 for the belts 9', 10' which carry the movable targets 9'', 10''. The track

grooves are depressed along their central por-tions, Fig. 12, so as not to be subject to wear or 100 undue friction with the fastening device which hold the targets on the belts.

For convenience the targets 9'' are made in the shape of animals and the targets 10'' are made in the shape of birds. Each movable target con-sists of a relatively thin plate bent laterally at the bottom edge to form a base 11 which is piv-105 oted or hinged at 11' to a clamp 12 on the belt Fig. 12. This clamp is U-shaped to embrace the bottom, one side edge and a portion of the top,

110

of the belt, the bottom portion being embedded in the belt to provide a smooth surface. A rivet 12' through the belt secures the top and bottom portions of the clamp to the belt. When upright 5 the targets incline slightly beyond the vertical to hold them upright when traveling through the range.

The belt 9' travels on pulleys 13 and the belt 10' travels on pulleys 14, Figs. 3 and 10, these 10 pulleys being mounted in the cabinet so that the belt 9' and its targets 9'' will travel across the pistol ranges in a higher plane than the belt 10' and its targets 10''. Side partitions 15 spaced from the side walls 15' of the cabinet extend forwardly 15 from the rear door 4 of the cabinet part way to the glass front 2 of the cabinet and then extend laterally to the side walls, thus forming end compartments 15'' in which the belt pulleys are positioned. Access to these end compartments is obtained through end doors 15'''.

The glass partition 3 is mounted on a wood base 3' which extends from front to back of the cabinet. The partitions 15 and 3' are provided with openings 16 to permit the movable targets 25 to pass through the partitions, Figs. 3 and 6. These openings are in the pistol ranges and are preferably of just sufficient height and width to permit passage of the movable targets when they are upright. Other openings 17 of any size are 30 provided in the partitions 15 to permit passage of the movable targets on the lower travel of the belts 9', 10'. Guide bars 18 are mounted on the partitions 15 within the end compartments 15'' adjacent the pulleys 13, 14 to hold the movable targets perpendicular as they travel around the pulleys, and guide bars 19 may be provided between the partitions adjacent the lower path of travel of the movable targets to maintain them in perpendicular position so far as they may be 35 necessary. Diverging guides 20 are provided at the entrance of the openings 16 to insure that the targets will enter the openings in upright position so that they may pass freely there-through.

Power from an electric motor 21 in the lower 40 part of the cabinet is transmitted through a shaft 22, and universal couplings 23', worm 23 and a worm gear 24 to a drive shaft 25 mounted in the cabinet. A drive chain 26 operates on a sprocket 50 wheel 27 on shaft 25 and on a sprocket wheel 28 on the shaft 14' which carries the pulleys 14 at the right Fig. 3. A gear 29 on the shaft 14' drives a gear 30 on shaft 31 which carries the pulley 13. Thus the belt 9' is caused to travel through the 55 pistol ranges from left to right, Figs. 3 and 10 and the belt 10' is caused by the same mechanism to travel through the pistol ranges from right to left, Fig. 3. The gear 30 is smaller than gear 29 which causes belt 9' and its targets to travel faster than belt 10'. The belts 9' and 10' are preferably made of leather and stretched to their limit before mounting on their pulleys so that they will have no slack in the pistol ranges to 60 obstruct the return of the pistol balls.

I also provide a group of other targets 32 which 65 are adapted to rise and fall in the pistol through the inclined support 8, these targets being positioned between the two sets of traveling targets Figs. 1, 4, 6 and 13 and slits 32' are provided in the plate 8 for these targets. The slits or openings 70 32' are just wide enough to admit the target when in upright position, and are lined with metal to prevent wear. In the structure shown there are two of these targets for each range. They 75 are mounted on a rocker bar 32'' which is pivoted

at 32''' below the wood partition 3' so that as this bar is rocked the targets in one range will rise into the range above the support 8 as the targets in the other range disappear below said support, and vice versa. The bar 32'' is rocked by the lever 33 which is pivoted at 33' at one end and has a pin and slot crank connection 33'' with the sprocket 27 on the shaft 25. The other end of the lever 33 is pivotally connected to a link 33''' which extends to and is pivotally connected to the rocker bar 32''. The disappearing targets 32 may represent human heads, duck heads or smoking pipes. They are in the form of flat thin plates, Fig. 13, which are pivoted at 34 to upstanding arms 35' on the rocker bar, so that the targets may fall over when struck by the balls against the inclined support 8, as shown in dotted lines. Springs 35 fastened on the arms 35' bear against the pivoted ends of the targets and yieldingly hold them in upright position. As the fallen targets are drawn downwardly through the slits 32' by the rocker arm, they are restored to upright position. The supporting arms 35' slide in L-shaped brackets 35'' fastened to the underside of the support 8. An oil soaked belt 100 packing 35''' is placed between each of the brackets and the adjacent plate 8 in contact with the arms 35' to keep said arms constantly lubricated. As best shown in Fig. 6, the rocker for the targets 32, which includes the arms 35', the bar 32'' and 105 the lever 33, is slightly inclined forwardly from a vertical plane. The pivotal connection of the targets 32 to the arms 35' and the disposition of the springs 35 is such that the targets are also supported in a plane slightly inclined forwardly 110 from a vertical plane. This inclination tends to prevent the targets from inadvertently pivoting from upright position in the reciprocation of the targets with the arms 35'.

An automatic coin operated spring pistol 36 115 of any suitable description is pivotally mounted at 36' and 36'' in an opening 37 in a face plate 37' on the front of the cabinet. The pistol, by means of its pivotal mountings on the face plate, can be swung vertically and laterally which makes it 120 capable of universal adjustment within the range to aim at any of the targets. The muzzle of the pistol projects into the cabinet and above the plate 7. This plate 7 is dished at the front and provided with an opening 38 to discharge the balls 125 which travel down the inclined plate into a tray 39, Figs. 6, 8 and 9, which is mounted on the pistol and is sufficiently elongated to receive the balls in any position to which the pistol is swung. The tray is pivotally mounted at 39' on the pistol 130 body for vertical movement and a spring 39'' yieldingly maintains the tray up against the underside of plate 7 regardless of the movement of the pistol. The bottom of the tray inclines to a depression 40 to receive the balls. A tubular member 41 connects the tray with the body of the pistol and the balls roll through this member into the magazine of the pistol. More balls are provided than the magazine of the pistol will hold 135 to provide for rapid firing, and the tray provides 140 a convenient receptacle for receiving the balls so that they will not remain on the range and in the path of the ball being shot.

If a traveling target is hit by a ball it will fall 145 down backward as far as the inclined support 8 will permit. In order to upright fallen targets before they pass through the opening 16 I provide curved guides 42 adjacent certain of the openings 16. Fallen targets will ride against these guides and thereby be uprighted before 150

- they enter the openings 16. A stationary target 43, Figs. 1 and 14, is mounted on each partition 15 and is provided with an opening 43' in front of a bell 44 also mounted on the partition 15. 5 These targets are in range of the pistols and if a ball passes into the opening 43' it will strike the bell and produce an audible sound. The bells are placed close enough to the targets to prevent the balls going through the openings 43'. 10 The coin mechanism of the pistol discharges the coin into a coin box 45, Figs. 2 and 6, for each pistol positioned in the bottom of the cabinet. A tubular chute 46 extends diagonally downward from the coin discharge opening of each pistol to 15 a point above the respective coin receptacle 45 to discharge the coins into these receptacles. The upper ends of these tubular chutes are flared to insure the entrance of the coin in any position to which the pistols are swung. The coin receptacles 45 are preferably in the form of rectangular metal trays or pans which can be removed from their compartments to empty them. These coin trays are kept within a strong wooden box built 20 within the cabinet. The cabinet has a hinged door 47 in its lower front wall through which access may be had to the coin trays. The wooden box has a top wall 48, rear wall 49 and end walls 50, the bottom wall being formed by the bottom 25 of the cabinet. A central partition 51 divides the box into two compartments, one for each coin 30 tray. The top wall has suitable diagonal openings for the coin chutes 46. The front wall of the box is formed by removable panels 52, one 35 on each side of the central partition for each coin tray compartment. One end of these panels have tongues 53 which fit in corresponding 40 grooves in the end wall of the box and the partition respectively. The other ends of the panels are provided with key operated locks 54, the bolts 45 of which engage with suitable keepers in the end wall and central partition respectively. The panels also have tongues 55 at their lock ends which engage shoulders formed on the central partition and end wall to prevent the panels from 50 being forced inwardly. The bolts of the locks, when shot, prevent the panels from being forced outwardly. The box which contains the coin 55 trays is made of very stout stock, as are also the movable front panels 52, and the panels fit snugly within the top, bottom, end walls and central partition of the box so that they cannot 60 be jimmied. This construction provides a very effective means for preventing pilfering which is somewhat prevalent in connection with this class 65 of coin operated machines. In order to gain entrance to both of the coin trays the culprit would have to force the locked cabinet door 47 and both of the removable panels. 66 Each pistol is provided with a counter or registering device 60 which is mounted on the bracket 67 extended from the pistol body. This counter 68 may be of any suitable type for the purpose. The one shown in the drawings, Figs. 6 and 8, has an operating arm 62 at its side which is rotatably mounted to swing through an arc and 73 actuate the counting device. The pistol has a finger piece (not shown) which is pushed when a coin is placed in the coin slot and this finger piece operates to discharge the coin into the coin 78 chute and to actuate the counter. A reciprocating bar 63 is operated longitudinally by this finger piece and this bar has an extension 64 having a slot 65 in which a lateral pin 66 on the coin arm 62 is positioned. The slot 65 is straight for a considerable portion of its length so that the bar 83 can move a considerable extent without actuating the counter arm. The inner end 67 of the slot is upturned at an angle and so proportioned that it will operate the counter at the end portion of the movement of the bar 63. 88 The relation of this angular slot portion 67 to the arm of the counter is such that it swings the arm only such distance as necessary to register one number on the counter and make it impossible to overthrow the counter arm by violently operating the finger piece. 93 The pistol with its receiving tray and the counting device are all mounted upon the face plate 37 to form a unit which may be readily detached or removed from the front of the machine for repairs or for shipping purposes. The face plate is set in a suitable recess in the front wall so that it will be substantially flush with the surface of the front wall of the cabinet, and a suitable opening 68 is provided in said cabinet wall for the pistol unit. The rear or inner side of the face plate has instanding lugs 6, Fig. 11, having holes which are engaged by the hooks or latches 70 for fastening the pistol unit in place. The latches 70 are pivoted at 71 on small metal plates 71' on the inside of the cabinet wall, and have laterally turned handles 72 disposed in position so that they can be reached through the door opening 47. Thus the pistol units can not be removed without the door 47 being open. 98 For shipping purposes I arrange to pack the pistols in the bottom of the end compartments 103 of the cabinet. As shown in Figs. 3 and 10, the partition wall 15 which forms the compartment has a slot 73 into which one end of the 108 face plate 37' is inserted. The other end of the face plate rests on a block 74 against which it is held by a pivoted latch 75. The butt of the pistol rests in a groove formed between two blocks 76 on the bottom wall of the cabinet. The pistol 113 units can thus be packed in the end of the compartments within the confines of the cabinet and are thereby protected against damage in handling and shipping. They are readily released from these compartments by swinging the latches 75 118 out of engagement with the face plates. 123 My invention provides a portable machine of simple construction which is adapted to furnish entertainment and amusement to operators, with the movable targets in continuous operation. The 128 drawings show the machine equipped with two pistol ranges which is desirable for simultaneous competitive shooting but the invention may be embodied in a single range machine or in a machine having more than two ranges. The pistols 133 are mounted to swing vertically and horizontally and can thereby be readily moved for aiming. The tray 39 is mounted on the pistol and moves therewith, and it is of a size and shape to register with the opening 38 in all positions of the 138 pistol. 143 I have shown the invention in the accompanying drawings in a form satisfactory for accomplishing the desired results but the invention may be embodied in other forms and constructions 148 and modified as required to meet different conditions and I reserve the right to make all such changes as fairly fall within the scope of the following claims: 149 I claim: 1. The combination of a cabinet having a pistol range therein, a floor for said range, targets adapted to be projected above and withdrawn below said floor, a rocker slightly inclined forwardly from a vertical plane, means pivotally 154

connecting the lower end of said targets to said rocker, means on said rocker and engaging said targets adjacent the pivotal connection thereof to align said targets with said rocker to be slightly inclined forwardly from a vertical plane, and means for operating said rocker.

2. The combination of a cabinet having a pistol range therein, a floor member for said range having openings therein, targets in said openings adapted to be projected above and withdrawn below the floor, means pivotally supporting the targets permitting them to fall when they are above the floor, and means for projecting said targets through said openings and above said floor and

10 for withdrawing said targets through said openings and below said floor whereby any fallen targets are uprighted while passing through said openings by engagement thereof with edges of the openings as they are withdrawn.

15 3. The combination of a cabinet having a pistol range therein, an inclined floor member for said range having openings therein, targets in said openings adapted to be projected above and withdrawn below the floor, means pivotally supporting the targets permitting them to fall when they are above the floor, a rocker bar beneath the floor on which the targets are mounted, a driving motor in the cabinet, a crank driven by said motor, and a link connecting the crank with

20 said rocker bar to operate the bar.

4. The combination of a cabinet having a partition therein to divide the cabinet into two pistol ranges, a floor member for said ranges having openings therein on each side of the partition, a rocker bar extending beneath the openings on both sides of said partition, targets pivotally mounted on said bar and positioned in said open-

ings, said targets being adapted to be restored to upright position by contact with the edges of said openings as they are withdrawn into said openings, and means for operating the rocker bar to raise and lower the targets.

5. The combination of a cabinet having a pistol range therein, a floor for the range having target openings therein, a rocker bar having upright arms vertically movable in said openings, guides for said arms beneath the floor, packing lubricant for the arms supported by the guides, and targets pivotally mounted on the upper ends of said arms which are projected above and withdrawn below the floor by said rocker bar.

6. In an amusement machine which has an inclined plate, target means on said inclined plate and including endless belts having targets thereon, said target means also including reciprocal targets, said inclined plate having openings therein through which said reciprocal targets may operate, a rocker, means connecting said reciprocal targets to said rocker for movement therewith whereby said reciprocal targets are projected through said openings to project above said inclined plate and are withdrawn below said inclined plate, the combination therewith of an operating mechanism including a drive shaft, means connecting said drive shaft to one of said endless belts, means connecting the other of said endless belts to the belt connected to the drive shaft and including portions operating one of said belts at a higher rate of speed than the other of said belts, and means having a pin and crank connection with said operating shaft for operating said rocker.
